UNITED STATES PATENT OFFICE.

GEORGE B. GLIDDEN, OF DIGHTON, MASSACHUSETTS, ASSIGNOR TO GEORGE FROST COMPANY, OF BOSTON, MASSACHUSETTS.

GARTER.

1,138,554.

Specification of Letters Patent.

Patented May 4, 1915.

Application filed August 24, 1914. Serial No. 858,229.

To all whom it may concern:

Be it known that I, GEORGE B. GLIDDEN, a citizen of the United States, residing in Dighton, in the county of Bristol and State of Massachusetts, have invented certain new and useful Improvements in Garters, of which the following is a specification.

My invention relates to gentlemen's garters of the class in which the stocking-ent 10 gaging clasp is suspended from the ends of the leg-band by a clasp-suspending device of general triangular shape comprising two tape members converging at their lower ends to which the clasp is attached and connected 15 at their upper ends by a separate piece of webbing.

It is very desirable that the garter, as a whole, should be as light as possible; that there should be economy in the use of mate- 20 rial, and that the leg-band should be strong and durable and such as to hold the tapes sufficiently wide apart in order to produce the most desirable strain on the ends of the leg-band and to properly support the clasp.

It is also desirable that the leg-band should 25 not be mutilated or cut into in any such way as to mar its appearance or lessen its strength. It is furthermore desirable that metal parts should, as far as possible, be omitted in the construction of the garter.

According to my invention, I provide a garter of the general class above mentioned and which embodies these desirable characteristics.

In the accompanying drawings I have shown several embodiments of my invention.

Figure 1 is a perspective view of the garter with my improvements applied. Figs. 2 and 3 are detail views, showing the manner 40 of connecting the narrow tapes of the triangle to the wider tubular leg-band and tab.

Fig. 4 is a perspective view of a modification, showing how the garter is constructed when two clasps are applied to the leg-band.

Fig. 5 is a detail view in perspective of the tubular fabric preferably employed in the construction of the leg-band and tab.

The leg-band A may be made of any suitable material. It is preferably, though not necessarily, non-elastic. It is provided with

a device a of well known construction for adjusting its length and one end of the leg-band is secured to the clasp-suspending device B in the manner hereinafter explained.

The opposite end of the leg-band carries a detachable fastening device a' adapted to

connect with a companion fastening device a^2 on a tab C attached to the suspending de- 60 vice B. Both the leg-band A and the tab C are preferably made tubular, as shown, and the diagonal tape members b , b' and cross tape b^2 of the clasp-suspending device connect with the leg-band and tab in the manner shown.

It will be observed that the tape members b , b' , b^2 are relatively narrow when com- 65 pared with the leg-band and tab. This construction provides a light skeleton suspending means for the clasp D which may be of any suitable construction. Furthermore, in- 70asmuch as the suspending tape members are relatively narrow their upper ends may be inserted into the inner ends of the tubular leg-band and tab and said tape members can be better disposed diagonally relatively to 75 the band and tab. It is not necessary to cut the tubular fabric at its sides or in fact at any point as the tape members are inserted into the open ends of the tubes and may be stitched thereto, as indicated at x .

While I have shown the part b , b' as made of a continuous length of tape, which is pref- 80 erable, they are in effect two distinct parts of the clasp-suspending device and I have therefore referred to them as two tape mem- 85 bers.

If the tape members b , b' were of the same width as the leg-band and tab they could not conveniently be given the inclination shown or properly secured to the tab and leg-band. 90 It will be observed by reference to Fig. 1, for instance, that the tape members b , b' have their outer edges inclined relatively to the lower edge of the leg-band and thus can be effected without giving any angular cut 95 to the inner or upper ends of the suspending tapes.

The narrow cross tape b^2 is preferably elastic and its ends also extend into the ends of the leg-band and tab, being fashioned 100 thereto at the same time with the ends of the diagonal suspending tape members. This cross tape, being elastic, serves to hold the leg-band on the leg with a yielding strain which does not produce any discomfort to 105 the wearer.

In some garters of this class two clasps are applied to each garter, and I have shown in Fig. 4 how my improvements may be embodied in such a garter. In this case the leg- 110 band and triangular suspending devices are similar to those above described, but one of the

suspending devices B is attached permanently to one end of the leg-band and it is also permanently attached to a connecting piece E, preferably of non-elastic tubular fabric, to 5 which is also attached one upper end of the other suspending device B which also carries the tab C. The connecting piece E in this case really forms a section or part of the leg-band. A garter made in this way is 10 much more comfortable than when cords are used to form the clasp-suspending device. It is also much more comfortable than where wide tapes are employed for this purpose, and furthermore there is great economy in 15 material, the narrow tapes being cheaper than cords or wide tapes and also providing a way by which the strain between the leg-band and the clasp at the proper angle may be most efficiently transmitted.

20 I claim as my invention:

1. A garter comprising a tubular leg-band, a tubular tab, a clasp and a clasp-suspending device comprising a plurality of narrow tapes having two end portions inserted into 25 the end of the leg band and secured thereto by stitching and two end portions inserted into the end of the tab and secured thereto by stitching.
2. A garter comprising a tubular leg-band, 30 a tubular tab, a clasp and a clasp-suspending device comprising narrow tape members con-

verging toward the clasp and connected therewith and which have their upper outer end portions on opposite sides of the clasp inserted into the ends of the leg-band and 35 tab and stitched thereto.

3. A garter comprising a tubular leg-band, a tubular tab and a triangular clasp-suspending device comprising a tape having its ends inserted into the ends of the leg-band 40 and tab, and two narrow diagonally arranged tape members having their upper ends inserted into the ends of the tab and leg-band and secured thereto and which are attached at their lower ends to a clasp. 45

4. A garter, comprising a tubular leg-band, a tubular tab, and a triangular clasp-suspending device, comprising a tape of elastic material having its ends inserted into the ends of the leg-band and tab, and two 50 narrow diagonally arranged tape members having their upper ends inserted into the ends of the tab and leg-band and secured thereto and which are attached at their lower ends to a clasp. 55

In testimony whereof, I have hereunto subscribed my name.

GEORGE B. GLIDDEN.
